CONTAINER

John M. Hothersall, Brooklyn, N. Y., assignor to
American Can Company, New York, N. Y., a
corporation of New Jersey

Application December 8, 1938, Serial No. 244,694

3 Claims. (Cl. 220—39)

The present invention relates to a sheet metal container or can having a compound gasket lined removable cover which is adapted to hold a vacuum in the closed container and which is secured in closed and sealed position on the container by interrupted screw threads, the invention having particular reference to a construction of closure which also includes elements for readily breaking the vacuum within the container when it is to be opened and this by an easy turning movement of the cover.

The invention constitutes an improvement or modification of that disclosed in my copending application Serial No. 46,939, filed Oct. 26, 1935, now Patent 2,180,357, issued Nov. 21, 1939.

Covers having a sealing gasket of compound lining material when applied to cans which have been vacuumized and when secured in place by interlocking screw threads, present difficulty in opening because the vacuum aided by the adhering effect of the compound, results in holding the cover so tightly on the can that considerable force is required to pry the cover loose and both cover and can are often distorted and damaged thus impairing the usefulness of the parts for reclosure purposes.

The instant invention contemplates overcoming this difficulty by providing a two-piece cover which when rotated in reverse, as when removing from the can, will lift an edge of the sealing member of the cover at one or preferably at two diametrically opposed places and thereby break the vacuum so that the cover as a whole may be readily removed.

An object, therefore, of the invention is the provision for a can adapted to be vacuumized of an improved compound lined cover which may be secured to the can by cooperating interrupted screw threads and locking elements wherein the cover may be turned down into tight hermetically sealed position on the can and locked against accidental loosening and dislodgment but yet may be easily operated when desired to break the vacuum within the can by a simple turning action so that the cover may be readily lifted off and used again as a reclosure.

Another object is the provision of such a can and cover wherein the cover is made in two pieces one of which is adapted to hermetically clamp the other onto the can and to have rotative movement relative thereto for prying loose an edge of the clamped member at one or more places and thereby to break the vacuum within the can when removing the cover so that the latter may be more easily removed.

Numerous other objects and advantages of the invention will be apparent as it is better understood from the following description, which, taken in connection with the accompanying drawing, discloses a preferred embodiment thereof.

Referring to the drawing:

Fig. 1 is a perspective view of a can and cover embodying the instant invention, the cover being shown removed from the can and in position thereabove ready for application to the can;

Fig. 2 is an enlarged fragmentary elevation of the cover assembled on the can in fully closed and sealed position;

Fig. 3 is a view similar to Fig. 2 showing the cover in a different position relative to the can as when removing the cover from the can; and

Fig. 4 is an enlarged sectional view taken substantially along the line 4—4 in Fig. 2.

As a preferred embodiment of the invention the drawing discloses a can comprising a cylindrical sheet metal body 11 having a side wall 12 and closed at its bottom end with a closure member which is secured to the body in a suitable seam 13. The upper end of the body is strengthened by an annular bead 14 which is struck outwardly from the body side wall. This side wall terminates above the bead in an inwardly bent edge curl 15 which provides a smooth top edge or cover seating ledge for the body.

After filling, the can is preferably closed with a removable two-piece sheet metal cover 21 which permits closure and sealing under vacuum and the cover may be used as a reclosure after the

can is once opened. This cover includes a substantially flat flexible sealing disc 22 and a separate annular clamping ring 23 for holding the disc in place.

The cover sealing disc 22 is formed with a flat circular countersunk panel 24 which at its outer edge merges into an annular inverted U-shaped flange 25. This flange provides a channel 26 in which a lining compound gasket 27 is carried.

The outer edge of the flange is or may be slightly outwardly flared as at 28. When the sealing disc is on the can the panel 24 is disposed in the mouth of the can and the flange 25 rests on top of and partially surrounds the body curl 15 as a seat, the gasket 27 being interposed between the flange 25 and the curl 15 as shown in Fig. 4. The gasket thus provides a hermetic seal between the can and the sealing disc. Adjacent the flange 25 the panel 24 is provided with a plurality of spaced inwardly extended projections 29 which

engage against the inner surface of the curl 15 and thus center the sealing disc on the can.

The sealing disc flange 25 is drawn down tight against the can seat or curl 15 by the annular clamping ring 23 which fits over the top of the flange 25. For this purpose the clamping ring is formed with a depending peripheral side wall section or skirt 31 which, when the cover is applied to the can, is outside of but closely adjacent the side wall of the can above the body bead 14. At its lower edge the ring side wall or skirt merges into an outwardly bent smooth edge curl 32. At its upper end the ring side wall merges into an inwardly bent curved wall section or flange 33 which surrounds the annular flange 25 of the sealing disc.

Adjacent the base of the curved wall section 33 where it merges into the side wall section 31 of the clamping ring, there is disposed an outwardly bent bead 34. Below this bead 34 there is provided, preferably on two diametrically opposite sides of the clamping ring, an inwardly pressed or struck curved boss or lug 35. The upper edge of the boss slopes inwardly from the ring side wall 31 and is cut through thereby providing a shoulder or cam section 36 which extends under but is spaced below the flared edge 28 of the sealing disc flange 25.

The cam sections 36 of the two bosses 35 loosely hold together the two pieces of the cover and form a unitary cover structure before the cover is applied to the can in which there may be free rotary movement between the ring 23 and the disc 22 when the cover is applied to the can, the metal to metal engagement of the curved wall section 33 and flange 25 permitting the proper sliding action. These two cam sections 36 are adapted to engage under the flared edge 28 of the disc flange 25 for removing the disc as will hereinafter be explained. Where the sealing disc 22 is of slightly larger diameter only one inwardly extending boss or lug 35 need be used to keep the two parts of the cover together or until the cover is applied to the can.

Screw thread sections formed in the body wall 12 above the bead 14 and in the cover ring wall section 31 provide for securing the cover to the can. In the can body wall there is provided annularly spaced thread sections 37 each of which includes a pair of vertically spaced and inclined interrupted threads 38 struck outwardly from the body side wall. The lower thread of each set may if desired merge at its lower end into the body bead 14.

In the cover ring wall section 31 there is provided annularly spaced individual and inclined interrupted threads 42 which are struck inwardly from the ring side wall to cooperate with the threads 38 in the body side wall. This general form of thread sections is often used in sheet metal cans for securing can and cover together.

When the cover 24 is applied to the can the cooperating pairs of interrupted screw threads 38, 42 are interengaged in the usual manner by a relative turning or rotative movement between the cover and the can, the threads 42 passing into the space between the threads 38. Knurled beads 45 struck out of the ring side wall section 31 just below the bead 34 provide a hand grip for facilitating this turning movement.

In applying the cover the sealing disc 22 turns with the ring 23 until stopped by engagement of the gasket 27 with the body curl 15. Thereafter the curved wall section 33 of the ring slides over the disc flange 25 while the screw threads slide

along each other until the cover is screwed down tight on the can.

In reverse movement of the ring 23 as when the can is opened by removal of the cover, the ring rotates and thus rises along the inclined threads while the sealing disc 22 remains stationary due to external atmospheric pressure and the clinging of the gasket compound onto the body curl 15. This continues until the cam sections 36 of the bosses 35 where two bosses are used engage under the flared edge 28 of the disc flange 25, and thus lifts vertically or prys loose a restricted portion of the flared edge of the sealing disc at two diametrical points. The sealing disc thus bends into an arch shape. This admits air into the can and thus breaks the vacuum.

When there is only one boss 35 the same prying action takes place but on one side only. The sealing disc again flexes or bends sufficiently to easily break the vacuum at a restricted place.

Thereafter the ring may be readily unscrewed, the cam section or sections 36 riding against the disc flange edge 28 and prying loose the compound gasket with ease and without damaging the gasket or distorting any can or cover parts. The cover may then be entirely removed and used again as a reclosure.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

Claims:

1. A container for easy opening comprising a container body formed with a top ledge defining an opening, a sheet metal two-piece unitary cover for closing said opening, said cover including a flexible cover disk having a peripheral flange adapted to seat on said ledge, a clamping member having an annular mounting with the flange of said disk and providing relative rotation between said disk and said member to pull down on said disk, sealing material on said flange for engaging said ledge, cooperating screw threads formed in said body and in said clamping member for positively moving said clamping member upwardly and downwardly, and said clamping member having thereon an inwardly extending portion disposed at a localized part only thereof, said portion lying beneath and spaced from said flange and adapted to engage said flange and lift the latter and the cover disk at a localized point out of sealing engagement with said ledge when the clamping member is rotated to release the same from the container body.

2. A container for easy opening comprising a container body formed with a top ledge defining an opening, a sheet metal two-piece unitary cover for closing said opening, said cover including a flexible cover disk having a peripheral flange adapted to seat on said ledge, a clamping member having an annular mounting with the flange of said disk and providing relative rotation between said disk and said member to pull down on said disk, sealing material on said flange for engaging said ledge, cooperating screw threads formed in said body and in said clamping member for positively moving said clamping

member upwardly and downwardly, and a plurality of individual inwardly extending circumferentially spaced cam projections on said clamping member, said projections extending beneath and spaced from said flange and adapted to engage said flange and lift the latter and the cover disk at localized points only out of sealing engagement with said ledge when the clamping member is rotated to release the same from the container body.

3. A container for easy opening comprising a container body formed with a top ledge defining an opening, a sheet metal two-piece unitary cover for closing said opening, said cover including a flexible cover disk having a peripheral flange adapted to seat on said ledge, an annular clamping member mounted on the flange of said

5 disk and providing relative rotation between said disk and said member to pull down on the disk, sealing material on said flange for engaging said ledge, cooperating screw threads formed in said body and in said clamping member for positively moving the latter upwardly and downwardly, and an integral partially cut inwardly extending lug on said clamping member projecting beneath and spaced from said flange and adapted to engage a portion of said flange and lift a localized peripheral portion only of the latter and the cover disk out of sealing engagement with said ledge when said clamping member is rotated to release the same from the container body.

15 JOHN M. HOTHERSALL.
